(57) **CLAIM**

The ornamental design for a camcorder, as shown and described.

DESCRIPTION

FIG. 1 is a front, top and right side perspective view of a camcorder showing our new design;

FIG. 2 is a rear, top and left side perspective view thereof;

FIG. 3 is a rear perspective view thereof showing the article with its monitor panel open;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken line showing on the drawing disclosure is for illustrative purposes only and forms no part of the claimed design. The line consisting of alternating long lines and short lines in the lower left portion of FIG. 9 indicates the conceptual border line between the claimed portions and the unclaimed portion.
